JOSEPH KLEE, OF MUNICH, GERMANY.

DISK WHEEL.

Application filed February 15, 1926, Serial No. 88,237, and in Germany February 16, 1925.

Disk wheels consisting of two iron disks which touch each other at the vaulted sides and are fastened in the center by a split boss, are well known. The disks of these wheels cannot be made out of thin sheet iron, for experiments have shown that the wheels then can easily be twisted by working pressures. This danger is the greatest when the connections of the special parts of the wheels are independent of the working pressures.

This invention avoids the disadvantages of such disk wheels and makes it possible to build them of thin sheet iron. The disk wheels consist of two iron disks which touch each other at the vaulted sides and are fastened in the center by a split boss; the flanges of the boss are sloped from without to within nearly to the center of the inside. Their cross-section forms a female cone which takes up the conical edges of the disks. These edges are directly fixed upon the outside edges of the boss flange by means of rivets, screws, etc., in order to prevent the edges of the disks from twisting. The rivets or screws, etc., in the disks support each other inside between the flanges of the boss.

A special construction of this disk wheel is shown in front view Figure 1 of the drawing and in an axial cross-section in Figure 2.

The body of the wheel consists of two circular thin disks of sheet iron, each of which has a flat circular bottom a^1 in the center, a conical part a^2 and a flat edge a^3 .

In the hollow part of each disk there is a boss in the form of a plate b^1 , b^2 , which fits exactly to the flat bottom a^1 and partially to the conical part a^2 ; these bosses have a collar b^5 for better bearing in the axle bushes.

Each disk is supported against the boss by an annular seat b^3 ; within the seat there is the annular space b^4 .

Disk and bosses have their conical parts a^2 , b^2 fixed together by rivets or screws c ; the rivet heads of the interior parts are rubbed down, touching each other exactly, when the disks are connected together.

The disks will be connected by five screws d , which fix at the same time the body of the wheel to the axle bush.

It is important that these screws d pass through the conical parts a^2 , b^2 of the disks and bosses; only in this way is it possible to avoid twisting even of very thin sheets.

This kind of fastening however is only

reliable in service when the disks and the base of rim are rigidly fixed together; only in this case are the disks exclusively stressed by compression.

For this purpose the base rim has on each side a circular flange e^1 fixed in radial direction, with an edge e^2 fitting exactly to the flat edge a^3 of the corresponding disk.

In spite of its vaulted form the disk will be elastic; a strong pressure on the bottom a^1 , directed against the flange e^1 , presses the edges e^3 and e^2 together throughout their entire extent and equally against the base rim e .

Under such a compression the edge a^3 of the disk will be riveted round about with the flange e^1 of the base rim e or better fastened by electrical welding.

As soon as the pressure against the bottom a^1 of the disk decreases, the disk endeavors to return to its former shape; but it will be prevented from doing so by the rivets or the welded joining. Therefore, the edge of the disk remains always fastened and compressed to the base rim e .

In the same manner both the disks are joined with the corresponding flanges and their bottom a^1 as well as the rivets c are compressed together when ready for use; therefore both the disks when in use are firmly supported by the base rim; even in taking curves the disks are only stressed by compression.

The connections, for example the rivets in the flanges e^1 and the edges a^3 will never be stressed by working pressures; even in operation they can only be stressed by the forces with which the elastic disk endeavors to regain its former shape.

The disk wheel with its thin disks according to the present invention has the toughness of a cast steel wheel.

It is possible to fasten the disks to the base rim by calking wholly or partially the edges a^3 of the disks with the edges e^2 , or by soldering.

At all events it will be necessary that the flanges e^1 are fixed to the base rim and that the disks with their edges a^3 are fastened to the inside of the flanges e^1 ; only in this case can the disks be perfectly supported.

Therefore the base rim e must be divisible at one place in order to give way when the disks will be introduced.

The annular space b^4 between the bosses is the opening for the key which separates

the bosses and disks from each other and makes it possible to dismount the base rim; even in this case it is not necessary to touch the pneumatic tire which therefore is safe-
5 guard against injuries when the wheel is dis- mounted.

What I claim is:

1. A disk wheel comprising disks converging from the wheel rim to the center there-
10 of, a boss having a splayed periphery en- gaging the converging portions of the disks, and means for securing said portions of the disks to the splayed part of the boss.
2. A disk wheel comprising disks converg-
15 ing from the wheel rim to the center there- of with the portions of the disk at the center of the wheel in contact with each other, a boss having an internal seat for the contact- ing parts of the disks and a splayed pe-
20 riphery engaging the converging parts of the disks adjacent the said seat and means

for connecting the splayed parts of the boss with the adjacent parts of the disks.

3. A disk wheel comprising sheet metal disks converging from the wheel rim to the 25 center thereof, a boss into which the inner ends of the disks extend, said boss having a splayed periphery, outer portions of the converging disks engaging the inner faces of the splayed periphery of the boss, and 30 means for connecting the disks to the boss.

4. A disk wheel comprising disks converg-
ing from the wheel rim to the center thereof, a boss having a splayed periphery with the inner face of which outer portions of the 35 disks engage, and means supporting each other between the splayed portion of the boss for connecting the disks to the boss.

In testimony whereof I hereunto affix my signature.

JOSEPH KLEE.
